HERMAN IHLENBURG'S
NEW COMBINATION TYPE ORNAMENTS FOR LETTER-PRESS PRINTING
DESIGN FOR A FONT OF PRINTING-TYPES.

Design No. 11,836, dated June 29, 1880.

Having now set forth my invention, what I claim as new is—

The design for a font of printing-types, as shown and described.

HERMAN IHLENBURG.

In presence of—
C. V. HUCHS,
H. METIUS.

UNITED STATES PATENT OFFICE.

HERMAN IHLENBURG, OF PHILADELPHIA, PENNSYLVANIA, ASSIGNOR TO
MACKELLAR, SMITHS & JORDAN, OF SAME PLACE.

DESIGN FOR A FONT OF PRINTING-TYPES.

SPECIFICATION forming part of Design No. 11,836, dated June 29, 1880.

Application filed June 4, 1880. Term of patent 14 years.

To all whom it may concern:

Be it known that I, HERMAN IHLENBURG, (assignor to MACKELLAR, SMITHS & JORDAN,) of the city and county of Philadelphia, Pennsylvania, have invented and produced a new and original Design for a Font of Printing-Types, of which the following is a specification.

The nature of my design is fully shown in the accompanying typographic impression, to 10 which reference is made; and it consists of a font of printing-types to be used for the formation of borders and ornamental surroundings for printed matter.

I will now proceed to describe my design, 15 referring to the figures placed over each member of the font in the typographic impression.

Nos. 1 and 15 are representations of butterflies.

No. 2 is a corner-piece representing leaves, 20 flower, and grasses grouped together.

No. 3 is a representation of two birds in flight.

Nos. 4 and 21 are representations of signs or symbols common to the Japanese language.

No. 5 is a group of leaves and grasses.

Nos. 6 and 7 are sections representing the bamboo-cane.

Nos. 8 and 9 represent sections of the bamboo-cane.

No. 10 is a representation of a large body of sedge.

No. 11 is a representation of a small body of sedge.

No. 12 is an end piece for a border composed of an upper line the left-hand portion of which

curves downward, and a lower line the left-hand portion of which curves upward, these two extremities united by a semicircular line upon the left, the whole figure shaded above,

below, and upon the left by a light line, following the line of the main figure, the face of

which is shaded by a series of light vertical lines and a ring.

From the left of the heavy curved line and beyond the light shaded line extends a heavy horizontal line crossed by a

short vertical line.

Nos. 13 and 14 are compound moldings formed by the heavy lines, shaded above and below

by light lines, the space between the heavy

lines shaded by a series of light vertical lines, 50 and the rings, in which are placed centrally the dots.

Nos. 16, 17, 18, and 19 are corner-pieces composed of representations of bamboo-cane bent or curved.

No. 20 is a group composed of grasses and Japanese lilies.

No. 22 is a representation of a body of sedge or grass.

Nos. 23, 24, 31, 34, and 40 may be designated 60 as representations of Japanese landscapes.

Nos. 25 and 26 are sections of folded drapery.

No. 27 is a figure formed by combining a section of the bamboo-cane, upon the right of which are placed the leaves, followed by the 65 flowers and grasses.

No. 28 is a corner-piece composed of a quarter of a circle or circular body, from which extend centrally upon the right the inclined lines, meeting at a point, the face of the corner-piece 70 shaded by a series of heavy and light lines, with rings, within which are placed centrally the dots; below the rings the heavy curved line, continued at its ends to form the fret, as shown, and the space below the curved line 75 shaded by the light and heavy lines, to give the appearance of concavity to this part (the pointed portion) of the figure.

No. 29 is a representation of a body of sedge or grass and a snail.

No. 30 is an arabesque, the upper portion of which is composed of a triangular figure shaded upon its face by a series of heavy and light lines and fine dots, the base-line of the figure curved downward and terminating upon 85 the right in the scroll, the line ornamented upon the left by the hook-like ornament, and crossed by a curve-line extending upward from the scroll and having the hook-like termination. From the base-line extends above and 90 to the right of the scroll a curved line looped and terminating in a petal-like ornament, this followed by a dot and a line terminating above and below in the hook-like terminations.

No. 32 is a branch of the palm-tree.

No. 33 is a representation of a mass of bamboo-leaves, upon which a bird is resting.

No. 35 is a section of bamboo-cane.

No. 36. The upper portion of the figure is formed of a rosette, from which are suspended the cords, between which is hung the basket, as shown. Upon the right of the figure are 5 the leaf-like ornaments.

No. 37 is the quarter of a circular figure, shaded upon the upper portion of its face by a series of light vertical lines, followed by the 10 heavy arch-shaped bodies; below this shaded by the heavy dots above and between the curling-like terminations, below and between which are the trapezoidal ornaments and a series of light vertical lines, which cover that portion of the face not occupied by the dots, curling-like 15 ornaments, and the trapezoids.

Nos. 38 and 39 are corner-pieces, formed by sections of the bamboo-cane, bent or curved, and crossed by sections of the bamboo-cane

extended horizontally above and beyond the curved portions.

No. 41 is an idealized group of leaves and 20 grasses.

No. 42 is a branch of the fern-plant.

No. 43 is a representation of a stork or heron 25 in the act of feeding.

No. 44 is a group of grasses and ferns combined.

Having now set forth my invention, what I 30 claim as new is—

The design for a font of printing-types, as 35 shown and described.

HERMAN IHLENBURG.
